UNITED STATES PATENT OFFICE

159,762

SPICE CONTAINER

Leo F. Touhey and Dorothy E. Touhey,
Minneapolis, Minn.

Application September 14, 1949, Serial No. 5,001

Term of patent 14 years

(Cl. D44—6)

To all whom it may concern:

Be it known that we, Leo F. Touhey and Dorothy E. Touhey, citizens of the United States, residing at Minneapolis, in the county of Hennepin and State of Minneapolis, have invented a new, original, and ornamental Design for a Spice Container, of which the following is a specification, reference being had to the accompanying drawings, forming part thereof.

Fig. 1 is a perspective view of a spice container, showing our new design.

Fig. 2 is a top plan view of the spice container.

We claim:

The ornamental design for a spice container, as shown.

LEO F. TOUEY.
DOROTHY E. TOUEY.
